US00D714959S

(12) **United States Design Patent**
Muraca

(10) **Patent No.:** **US D714,959 S**
(45) **Date of Patent:** **** Oct. 7, 2014**

(54) **BEAM DUMP ASSEMBLY**

(71) Applicant: **Nuclea Biotechnologies, Inc.**, Pittsfield, MA (US)

(72) Inventor: **Patrick J. Muraca**, Pittsfield, MA (US)

(73) Assignee: **Nuclea Biotechnologies, Inc.**, Pittsfield, MA (US)

(**) Term: **14 Years**

(21) Appl. No.: **29/436,506**

(22) Filed: **Nov. 6, 2012**

(51) LOC (10) Cl. **24-03**

(52) U.S. Cl.

USPC **D24/232; D16/137**

(58) **Field of Classification Search**

USPC D24/231-233; D16/130-131, 136;
359/613-615; 250/396 R, 311;
273/402; 219/121.6, 121.61; D21/302

(57) **CLAIM**

The ornamental design for a beam dump assembly, as shown and described.

DESCRIPTION

FIG. 1 is a front view of the beam dump assembly.

FIG. 2 is a back view of the beam dump assembly.

FIG. 3 is a left side view of the beam dump assembly.

FIG. 4 is a right side view of the beam dump assembly.

FIG. 5 is a top view of the beam dump assembly.

FIG. 6 is a bottom view of the beam dump assembly; and, FIG. 7 is a cross-section view of the beam dump assembly taken along line 7-7 of FIG. 3.
